CLAIM

The ornamental design for a power plug, as shown and described.

DESCRIPTION

FIG. 1 is a front perspective view of a power plug.

FIG. 2 is a front side view of the device of FIG. 1.

FIG. 3 is a rear side view of the device of FIG. 1.

FIG. 4 is a left side view of the device of FIG. 1.

FIG. 5 is a right side view of the device of FIG. 1.

FIG. 6 is a top side view of the device of FIG. 1; and,

FIG. 7 is a bottom side view of the device of FIG. 1.

In the drawings, the broken lines are for the purpose of illustrating portions of the power plug that form no part of the claimed design.
